UNITED STATES PATENT OFFICE

2,457,534

BUTTON BLANK FEEDING ATTACHMENT

Joseph A. De Marco, Brooklyn, N. Y.

Application January 7, 1947, Serial No. 720,553

1 Claim. (Cl. 79—17)

1

This invention relates to new and useful improvements and structural refinements in button making machines, and the principal object of the invention is to provide a blank feeding attachment which may be conveniently and effectively employed for mechanically depositing the blanks on the chucks of the conveyor with which such machines are usually provided.

Conventionally, the button blanks are deposited on the chucks by hand and the speed of the machine is therefore more or less dependent upon the speed of the manual feeding operation.

Accordingly, by employing a mechanical feeding device, the feeding operation can be kept more in step, as it were, with the manufacturing machine and the latter may possibly be operated at higher speed than has been previously considered practical.

Furthermore, manual feeding demands individual handling of the blanks by the operator and since the latter is primarily concerned with the depositing of the blanks on the chucks at the fastest possible rate, it becomes readily apparent that the operator has no time to inspect the individual blanks which he is handling. As a result, a considerable number of defective blanks are fed to the machine and the useful output thereof is greatly diminished. However, by employing a mechanical feeding device, the operator will have ample time to inspect the blanks as they pass through the feeding attachment, and the foregoing disadvantage will thus be eliminated.

A further object of the invention is to provide a feeding attachment which is simple in construction, which may be readily installed in position on the machine, and which is automatically actuated by the operation of said machine, so that it may accurately keep in step with the same.

An additional object of the invention is to provide a feeding attachment which will not easily become damaged and which will readily lend itself to economical manufacture.

With the above more important objects in view and such other objects as may become apparent as this specification proceeds, the invention consists essentially of the construction and arrangement of parts as shown in the accompanying drawings in which:

Figure 1 is a top plan view of the invention, showing the same at the commencement of the feeding stroke;

Figure 2 is a top plan view, similar to that shown in Figure 1, but showing the invention at the conclusion of the feeding stroke;

Figure 3 is a cross sectional view, taken sub-

2

stantially in the plane of the line 3—3 in Figure 1; Figure 4 is a cross sectional view, taken substantially in the plane of the line 4—4 in Figure 2;

Figure 5 is an underside plan view of the invention; and

Figure 6 is an end view thereof, taken in the direction of the arrow 6 in Figure 1.

Like characters of reference are used to designate like parts in the specification and throughout the several views.

Referring now to the accompanying drawings in detail, the invention consists of a feeding attachment designated generally by the reference character 10, the same embodying in its construction an elongated plate 11 which may be mounted in any suitable manner above the conveyor 12 with which the button making machine is usually provided.

The conveyor 12 is customarily equipped with a row of spaced chucks 13 which are adapted to receive the button blanks, and the underside of the plate 11 is formed with a longitudinally extending groove 14 which provides what may be referred to as a passage for the chucks.

25 The upper surface of the plate 11 is provided with a longitudinally extending channel 15, one end of the latter being closed as at 16, while its remaining end terminates in an enlarged opening 17 which is in communication with the passage 14.

30 A blank delivery trough 18 extends downwardly from a suitable hopper (not shown) and communicates at the lower end thereof with the channel 15 adjacent the opening 17. The channel 15 receives a slidably ejector bar 19 and the latter is provided medially of its length with an upstanding pin 20, as will be clearly apparent. The purpose of the bar and pin will be hereinafter more fully explained.

35 40 A pair of dogs 21, configurated as is best shown in Figure 5, are provided adjacent the underside of the plate 11, each of the two dogs being secured by a suitable set screw 22 to a pin 23. The two pins 23 extend through the plate 11 on the relatively opposite sides of the passage 14 and each pin is rotatably mounted, preferably in a ball bearing 24. It will be observed that the dogs 21 are relatively opposed and that they project into the passage 14, as will be clearly understood.

45 50 Each of the pins 23 also carries a lever 25, the two levers being disposed adjacent the upper surface of the plate 11. One end of each of a pair of links 26 is mounted on the aforementioned pin 20 and the remaining end of each link is pivoted as at 27 to one of the levers 25. The links 26 are

sectionally relieved so that they may be disposed in the same horizontal plane.

Finally, resilient means assuming the form of an elastic band 28 is anchored at one end thereof to a pin 29 extending upwardly from the plate 11, while the remaining end of the band is attached to a pin 30 provided on the ejector bar 19. It will be noted that the band 28 will urge the bar toward the closed end 16 of the channel 15.

When the invention is placed in use, the device is mounted above the conveyor belt 12 as has already been explained, so that the belt moves in the direction of the arrow 31. The button blanks 32 are fed from the hopper (not shown) through the trough 18 and into the channel 15, 15 and assuming the plunger 19 to be in the position shown in Figure 1, it will be noted that only one of the blanks 32 can be accommodated in the channel at one time.

As the conveyor 12 travels in the direction of the arrow 31, one of the chucks 13 will engage the dogs 21 and will swing them outwardly as indicated at 33. The movement of the dogs will be transmitted through the medium of the pins 23 to the levers 25, which in turn, by actuating the links 26, will slide the ejector bar 19 in the direction of the arrow 34.

The sliding of the bar 19 will eject the button blank immediately in front of the bar into the opening 17, and matters are so arranged that the button blank is deposited upon the particular of the chucks 13 which is actuating the dogs 21. This is best shown in Figure 2, and it will be observed that when the bar 19 is in the ejected position, it will cover the outlet of the trough 18, so that the blanks in the trough are not permitted to descend into the channel 15.

When the dogs 21 have been spread apart sufficiently to clear the conveyor chucks, the resiliency of the band 28 will return the various movable parts to their starting position, in readiness for the next cycle of operation which will occur as soon as the next chuck engages the dogs 21.

It is believed that the advantages and use of the invention will be clearly apparent from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

10 In association with a conveyor including a row of blank receiving chucks, a feeding attachment comprising in combination, an elongated plate positioned above said conveyor and provided in the underside thereof with a longitudinally extending passage for said chucks, the upper surface of said plate being formed with a longitudinally extending channel terminating at one end thereof in an opening communicating with said passage, an ejecting bar slideable in said channel, a blank delivery trough communicating with said channel adjacent said opening, a pair of rotatable shafts extending through said plate on the relatively opposite sides of said passage, a pair of transversely aligned coacting dogs secured to the lower ends of said shafts and projecting into said passage, a pair of levers mounted on the upper ends of said shafts, an upright pivot pin provided medially the length of said bar, a pair of links each mounted at one end thereof on said pin, the remaining end of each link being pivoted to one of said levers, the engagement of said chucks with said dogs sliding said bar toward said opening, and tensioning means for returning said bar to its initial position.

35 JOSEPH A. DE MARCO.
